UNITED STATES PATENT OFFICE.

WILLIAM T. NELSON, OF DAYTON, OHIO.

SAW-FILING MACHINE.

1,080,921.

Specification of Letters Patent

Patented Dec. 9, 1913.

Application filed August 17, 1909. Serial No. 513,317.

To all whom it may concern:

Be it known that I, WILLIAM T. NELSON, a citizen of the United States, residing at Dayton, in the county of Montgomery and State of Ohio, have invented certain new and useful Improvements in Saw-Filing Machines, of which the following is a specification.

My invention relates to saw filing machines and is adapted to file the teeth of hand-saws, jig-saws, band-saws, or saws of types other than circular saws in which the teeth are arranged in substantially a straight line.

15 The object of the invention is to simplify the structure as well as the means and mode of operation of such devices whereby they will not only be cheapened in construction but will be rendered more efficient and positive in operation, easily operated and unlikely to get out of repair.

20 A further object is to provide improved mechanism whereby the device will be under the control of the operator and whereby it may be adjusted to different angles, thereby giving the cutting face of the saw teeth greater or less degree of inclination.

25 Further objects are to provide improved means for lifting the file from engagement with the saw during its retrograde movement and also to provide improved means for advancing the saw during the return movement of the file.

30 With the above primary and other incidental objects in view as will more fully appear in the specification, the invention consists of the features of construction, the parts and combinations thereof, and their mode of operation, or their equivalents as 40 hereinafter more fully described and set forth in the claims.

Referring to the drawings, Figure 1 is a plan view of the assembled machine. Fig. 2 is a side elevation thereof viewed in the 45 direction as indicated by the arrow in Fig. 1. Fig. 3 is a rear elevation in which the swinging frame is shown in a position substantially at right angles to the base member. Fig. 4 is a detail perspective view of one end 50 of the base member showing the adjustable and sliding connections of the saw-carriage. Fig. 5 is a detail perspective view of the adjustable fulcrum connection of the operating lever for the step by step mechanism. Fig. 6 is a detail perspective view of the file 55 carrying member. Fig. 7 is a detail view of the actuating cam of the file carrying

member showing the same in its operated position.

Like parts are indicated by similar characters of reference throughout the several views.

In constructing the device there is employed a main base member 1 adjacent to the opposite ends of which are carried adjustable uprights or standards 2. The uprights 2 may be attached to the base 1 in any suitable manner but are preferably provided with lateral arms 3 thereby forming an L-shaped member, the arm 3 of which 70 projects through a keeper 4 secured on the base 1 and is adapted to be clamped therein in its adjusted position by a set screw or thumb-nut 5. The upper portions of the standards 2 are slotted as at 6 in which is 75 adjustably carried a longitudinal supporting bar 7 upon which is mounted the saw-carriage. The supporting bar 7 may be adjusted vertically within the limits of the slots 6 and is secured in its adjusted position 80 by set screws or thumb-nuts 8. The supporting bar 7 is preferably either rabbeted or formed with beveled edges as at 9 to receive the gibbed supports 10 of the saw-carriage. The saw-carriage comprises two lon- 85

gitudinal parallel clamping bars 11 between which the saw to be filed is impinged by means of clamping screws or thumb-nuts 12. The clamping bars 11 are slidably mounted upon the longitudinal supporting bar 7 by 90 means of the gibbed supports 10 to which one of the clamping bars 11 is attached. To provide sufficient resistance to hold the saw-carriage in its adjusted position on the supporting bar 7 there is provided on each of 95

the gibbed supports 10 a spring member 13 bearing upon the surface of the supporting bar 7 the tension of which is adjustable by means of screws passing through the spring member 13 and engaging the gibbed support 100 10. Attached to the opposite side of the clamping bars 11 are pockets 15 in which is carried a longitudinal serrated rod or rack 16, the serrations of which are in the form of ratchet teeth. Slidably mounted upon 105 the serrated rod 16 is a head 17 on which is carried a spring actuated pawl 18 engaging the serrations of the rod 16. Pivotally supported on a bracket 19 projecting from the base 1 is an oscillating lever 20 connected by 110 a link 21 with the sliding head 17. By the oscillation of the lever 20 the sliding head 17 will be reciprocated upon the serrated rod 16, the pawl 18 being held in engagement

with the serrations of the rod 16 by the spring 22. As the sliding head 17 is reciprocated in one direction, to the left in Fig. 3, the pawl 18 engaging the serrations of the 5 rod 16 will advance the saw-carriage in unison with the movement of the head 17, but upon the return movement of the head 17 the pawl will ride freely over the serrations of the rod 16, the saw-carriage remaining at rest, and will engage the rod preparatory to advancing it an additional step 10 at the next operation.

Pivottally connected to the base 1 at the point 23 is a swinging frame comprising two 15 horizontal members 24 and 25 and the vertical member 26. The horizontal member 25 is extended beyond the member 26 and formed into the handle 27 by which the swinging frame may be moved about its 20 pivotal connection 23. To support the swinging frame and secure it in its adjusted position, the lower end of the vertical member 26 is bifurcated and engages a curved member 28 supported on the base 1.

25 A thumb-nut or set screw 29 provides means whereby the frame may be secured in its adjusted position. Supported on the horizontal member 24 is a swinging frame comprising the pivoted arms 30 connected at 30 their extremities by a slotted bar 31. Mounted on the bar 31 and adapted to reciprocate thereon within the limits of the slot 32 is a reciprocating head 33 which comprises the file carrying member and is provided with 35 file clamping devices 34 which may be of any approved design. The file 35 is securely clamped by means of the devices 34 and moves in unison with the reciprocating head 33. Suitably journaled on the vertical mem- 40 ber 26 of the swinging frame is a drive shaft 36 carrying a crank or as shown in the drawings a disk 37 having thereon a wrist-pin connected by a pitman rod 38 with the reciprocating file carrying head 33. It is ob- 45 vious that upon rotation of the drive shaft 36 the head 33 will be reciprocated upon the bar 31 and the file 35 moved across the saw clamped in the saw-carriage. There is also 50 pivotally connected to the arms 30 a reciprocating bar 39 having a head 40 adapted to be engaged by a cam 41 carried on the drive shaft 36 adjacent to the inner side of the disk 37. The cam 41 if desired, may directly engage the head 40 of the reciprocating rod 55 39. However, to insure more even move- 60 ment of the parts a swinging arm 42 is pivoted upon the horizontal member 24 and is interposed between the cam 41 and the head 40 of the bar 39. Upon rotation of the 65 shaft 36 the cam 41 is adapted to engage the swinging arm 42 which in turn engages the head 40 of the reciprocating bar 39 and forces said bar in a horizontal direction which causes a swinging movement of the

ted bar 31 and the reciprocating head 33 above their normal or working position as shown in dotted lines in Fig. 2. This movement of the bar 39 and swinging arms 30 is against the tension of a spring 43 by 70 which the parts are returned to normal position when the cam 41 has been rotated sufficiently to disengage it from the swinging arm 42 and head 40. The cam 41 is so located upon the drive shaft 36 in relation to the connection of the pitman 38 and disk 37 that during the forward movement of the reciprocating head 33 the parts will be in their lowermost or normal position as shown by solid lines in Fig. 2, but, as the head 33 75 approaches the limit of its forward stroke the cam 41 will reciprocate the bar 39 thereby oscillating the arm 30 and elevating the head 33 and file carrier thereby and will hold the parts in their elevated position as 80 shown by dotted lines, Fig. 2, during the retrograde movement of the reciprocating head 33. As the head 33 approaches the limit of its rearward movement the cam 41 85 will disengage the bar 39 and permit the return of the parts to normal position by means of the spring 43, the movement of said parts being limited by a stop arm 44 secured to the member 24 the surface of 90 which is preferably cushioned by means of 95 rubber or similar means. During the retrograde movement of the file while in its elevated position, the saw-carriage will be advanced a predetermined distance, equivalent to two teeth of the saw being operated upon. 100 This is accomplished by means of the step by step mechanism before described, includ- 105 ing the pawl 18 engaging the serrated rod 16. These parts are operated from the main shaft 36 by means of an eccentric 45 connected at 46 to an operating lever 47 which in turn is connected by a universal joint to the point 48 with the oscillating lever 20 of the step by step mechanism. Inasmuch as saws vary in regard to the number of 110 teeth per inch means must be provided for varying the step by step movement to correspond with the particular saw being operated upon whereby the advance step will be equivalent to two teeth. It is to be under- 115 stood that the inclination of the cutting face of successive teeth of a saw is in opposite directions. For this reason, the swinging frame will be set at the proper inclination with the saw carriage and each alternate tooth operated upon in the same direction after which the swinging frame will be read- 120 justed to the opposite inclination and the intermediate teeth filed. Thus, at each operation it is necessary to advance the saw 125 the distance of two teeth. To vary the step by step movement there is provided an adjustable fulcrum for the operating lever 47 which comprises a standard 49 adjustably secured upon the frame member 25 by means 130

of a thumb-nut 50 whereby the standard 49 may reciprocate upon the member 25. Pivotedly secured to the standard 49 is a fulcrum block 51 through which the lever 47 extends. The construction is such that when the standard 49 is shifted upon the frame member 25 the fulcrum block 51 will slide upon the lever 47 thereby varying the relative proportions of the two arms 10 of said lever 47 and giving to the working end of the lever a greater or less stroke whereby the oscillating lever 20 of the step by step mechanism will be oscillated to a greater or less degree thereby shifting the 15 sliding head 17 throughout a greater or less movement and moving the saw-carriage a corresponding distance.

In lieu of the shifting fulcrum for the lever 47 as described, different serrated rods 20 16 may be employed each rod having serrations therein of different length and corresponding to the extent of two teeth of the saw with which it is to be used in which case the serrated rod, having proper serrations, would be substituted each time it was 25 desired to operate upon a saw of different character.

From the above description it will be apparent that there is thus produced a machine of the character described, possessing 30 the particular features of advantage before enumerated as desirable but which obviously is susceptible of modification within the scope of the appended claims in its form, 35 proportion, detail construction, and arrangement of parts, without departing from the principle involved, or sacrificing any of its advantages.

Having thus described my invention I 40 claim:

1. In a machine of the character described, a base, a saw carriage movably mounted on said base, means for automatically advancing the carriage through a step by step movement comprising a reciprocating head, a pawl carried by said head, a rack bar carried by the carriage and engaged by the pawl, a swinging frame pivotally supported on said base and adjustable to 45 different degrees of inclination therewith, a reciprocatory file carried on said frame and adapted to engage the saw in an angular direction according to the adjustment of said frame, swinging arms on which the 50 file is supported, means to oscillate the arms to lift the file during its retrograde movement and means carried upon the swinging frame to reciprocate the pawl carrying head during the retrograde movement of 55 the file regardless of the angular adjustment of the swinging frame, substantially as 60 specified.

2. In a saw filing machine, a two part

main frame the parts of which are adjustable to different angular positions in relation with each other, a saw carriage adjustably mounted on one of the frame members, a rack bar connected with said carriage, a reciprocating head, a pawl carried thereby and engaging the rack bar, actuating means carried by the other portion of the two part frame adapted to cause the reciprocation of said head in all positions of relative angular adjustment of the frame parts, substantially as specified. 65

3. In a saw filing machine, a two part frame, the parts of which are adjustable to different angular positions in relation to each other, a saw carriage adjustably mounted on one of the frame parts, means to advance the carriage through a step by step movement including a rack bar, a reciprocating head and pawl carried thereby engaging the rack bar, a pivoted actuating lever carried on the portion of the frame 80 with the carriage and adapted by its oscillation to actuate the reciprocating head, a second actuating lever carried upon the other portion of the two part frame and engaging the first mentioned lever, whereby 85 the oscillatory movement of the second mentioned lever will be transmitted to the first mentioned lever, a reciprocatory file, and means to oscillate the second lever during 90 the retrograde movement of the file, substantially as specified. 95

4. In a machine of the character described, a base, a longitudinal supporting bar carried on the base, a movable saw carriage, gibbed supports on the carriage engaging the supporting bar, spring members carried by the carriage and engaging the bar to afford resistance to the advance movement of the carriage. 100

5. In a machine of the character described, a base, a movable saw carriage, a reciprocating file, parallel pivoted swinging arms, a supporting bar carried thereby on which the file is reciprocated, means to move the arms about their pivotal points at predetermined points in the sequence of operation of the machine comprising a longitudinal reciprocating bar pivotally connected to both the swinging arms moving in unison with and in parallel relation to the supporting bar, and a cam member adapted to reciprocate said bar whereby the file will be elevated out of contact with the saw during its retrograde movement. 110

In testimony whereof, I have hereunto set 120 my hand this 3rd day of August A. D. 1909.

WILLIAM T. NELSON.
